BOOT AND THE LIKE

Leo J. McGarry, Watertown, Mass., assignor to
 The B. F. Goodrich Company, New York, N. Y.,
 a corporation of New York

Application November 17, 1949, Serial No. 127,831

6 Claims. (Cl. 36—4)

1

This invention relates to footwear and pertains more particularly to footwear designed to cover the shoes of the wearer, such as boots, galoshes, rain shoes, and the like.

It is an object of this invention to provide an article of footwear which has an increased resistance to frictional forces exerted on the heel portions of the article.

It is also an object of this invention to provide an article of footwear which may be easily pulled on or removed from the foot.

Another object of this invention is to provide an article of footwear whose innermost vertical surface is seamless at the extreme rear heel portions.

A further object of this invention is to provide an article of footwear which is comfortable when worn on the foot.

Other objects of this invention will be apparent from the drawings and description which follow.

One conventional type of boot or overshoe comprises a flexible upper which extends upwardly from the instep level on the foot, and a relatively stiff foot-enclosing shell extending from the sole to the bottom margin of the upper and joined to the latter by a horizontal lap-seam generally parallel to the sole. The two vertical margins of the shell are joined to each other at the extreme rear heel portion of the boot or overshoe forming a vertical seam. This construction has been adopted because it permits boots to be made without the necessity of providing a last for the upper; the foot-enclosing shell is lasted and the upper is merely draped around the shank of the last, depending from the edge of the shell to which it is secured by a lap seam.

Although this expedient results in a greatly reduced cost of construction because the necessity for a full last for the upper is eliminated, it is subject to certain disadvantages. As the shoe or boot is pulled on or removed from the foot of the wearer, frictional forces are exerted on the horizontal and vertical seams in the heel portion which tend to destroy the seams. The horizontal and vertical seams occurring at the extreme rear heel portion of the shoe or boot are disadvantageous in that they provide an uneven surface which rubs against the heel of the wearer's shoe, the uneven surface causing excessive wear.

I have found that the various disadvantages inherent in such a construction, as pointed out above, may be eliminated by omitting the rear portion of the foot-enclosing shell and extending the upper downwardly to the sole in this portion.

2

of the footwear to provide a seamless heel portion.

For a clearer understanding of this invention, specific reference will be made henceforth to a boot, however, it will be understood that I contemplate the use of this invention in other articles of footwear in which much the same problems arise, such as galoshes, overshoes, and the like.

10 In the drawings:

Fig. 1 is a side elevation partly broken away and in section of a boot embodying this invention;

15 Fig. 2 is a section on the line 2—2 of Fig. 1; Fig. 3 is a section on the line 3—3 of Fig. 1; and Fig. 4 is a section on the line 4—4 of Fig. 1.

A boot made in accordance with my invention as shown in Fig. 1 comprises a flexible upper member 10 which generally extends up to the 20 knee of the wearer covering the calf of the leg, a stiff foot-enclosing shell 11, and an insole 12.

The upper 10 consists of a fabric lining 13 which is preferably a knitted fabric, such as light net, coated with rubber-like material on its outer 25 face by a calendering process. Opposing margins 14 and 15 of the upper 10 are cemented together forming a lap seam down the front of the boot as shown in Fig. 4 to provide a limp, flexible leg-enclosing upper member. The heel portion 16 of upper 10 extends a short distance, preferably 30 from $\frac{1}{4}$ to $\frac{1}{2}$ inch, under the insole 17.

The foot-enclosing shell 11 is constructed preferably of a knitted fabric, such as heavy net, coated with a rubber-like material and is of sufficient stiffness to maintain the desired shape 35 without additional support. The rubber material of the shell preferably is thicker than that of the upper. For example, it may be a thickness of .032" in the shell as compared with a thickness of .018" in the upper. As shown in Fig. 1, the shell 11 is lap seamed to the upper 10 along a horizontal zone extending forwardly from beneath the ankle on each side of the foot and is lasted under the insole 17 a short distance, preferably $\frac{1}{4}$ to $\frac{1}{2}$ inch, along its bottom margin.

40 The vertical rear margins 18 of the shell 11 are lap seamed to upper 10 forming vertical junctures at the quarter portions of the boot eliminating a horizontal seam at the rear heel portion of the boot.

45 A foxing strip 20 of rubber-like material whose upper margin is adhered over the bottom margin of the upper 10 extends over the horizontal seam formed by the juncture of the upper margin of shell 11 and the bottom margin of the upper 10.

and is secured along its bottom margin to shell 11.

The heel counter 21 of rubber-like material provided with a woven fabric reinforcing layer is adhered along its upper margin to the outer surface of upper 10 and extends downwardly over the heel portion of the upper 10 and the rear portions of foxing strip 20 and is adhered along its bottom margin to outsole 12.

A toe cap 22 of rubber-like material provided with a woven fabric reinforcing layer is adhered over the outer face of the toe portion of shell 11 and provides reinforcement and strength to this portion of the boot.

To construct the boot the upper 10, the shell 11, the foxing strip 20, and the heel counter 21 are cut to the desired contours from flexible rubber-like sheets reinforced with fabric material. An insole 17 is placed on a last 23; the shell 11 is lasted over it; and the heel portion of the upper 10 is lasted over the insole, the opposing margins 14 and 15 of upper 10 having been previously lap seamed to each other. The bottom margin 25 of upper 10 is lap seamed over the upper margin 26 of shell 11 and the vertical margins 18 of the shell 11 are lap seamed over margins 27 of the upper 10. The bottom margin 28 of the heel portion 16 of the upper 10 is lasted to insole 17.

The foxing strip 20 is placed over the horizontal lap seam formed by the juncture of the bottom margin 25 of the upper 10 and the upper margin 26 of the shell 11. The heel counter 21 is lasted over the heel portion 16 of upper 10 and the rear portions of the foxing strip 20. The toe cap 22 is drawn and shaped over the toe portion of the shell 11. The outsole 12 is then applied, and the assembly is vulcanized to produce an integral unit.

By means of this invention it is possible to build a boot without using a full last for the upper, thus reducing greatly the cost of the last, and at the same time avoiding the disadvantages inherent in the constructions previously made on such a last. There is provided a boot with a limp, highly flexible leg-enclosing upper extending upwardly from about ankle level, together with a relatively stiff, form-retaining foot-enclosing shell extending from the upper to the sole around the fore part of the boot, so that the heel portion is free from seams, the upper being lasted to the sole in the heel portion from quarter to quarter. Elimination of seams in this zone prevents breakdown of the boot during use.

The elimination of the aforementioned horizontal and vertical seams at the extreme rear heel portion of the boot or shoe provides a smooth uninterrupted vertical surface at the heel portion of the article facilitating insertion or removal of the foot from the article. The uninterrupted surface at the heel portion of the article offers an additional advantage, in that there are no uneven surfaces to chafe the foot or shoe over which the article of footwear is worn.

It is clear that obvious modifications and variations may be made without departing from the spirit and scope of my invention as defined in the appended claims.

I claim:

1. An article of footwear comprising a sole member, a flexible upper member extending above ankle level and extending around the fore part of said article with its forward lower margin at about mid-instep level, said upper member being secured to said sole member only along a zone extending rearwardly from substantially the heel breast portion on each side of said article, and

a form-retaining shell extending around the fore part of said article from the level of the sole to about mid-instep level, said shell having two generally parallel margins and being secured to said sole member along one of said margins and secured along the other of said margins to the lower margin of said upper member.

2. An article of footwear comprising a sole member, a flexible upper member extending above ankle level and extending forwardly around the fore part of said article with its forward lower margin at about mid-instep level, said upper member being secured to said sole member only along a zone extending rearwardly from substantially the heel breast portion on each side of said article and said upper member having a seamless vertical innermost surface along the extreme rear heel portion of said article, a form-retaining shell extending around the fore part of said article from the level of the sole to about mid-instep level, said shell having two generally parallel margins and being secured to said sole member along one of said margins and secured along the other of said margins to the lower margin of said upper member, and a reinforcing counter overlying the outer face of said shell and upper member around the heel of said article rearwardly of the shank of said sole member.

3. An article of footwear comprising a sole member, a flexible upper member extending at least to mid-calf height and extending forwardly around the fore part of said article with its forward lower margin at about mid-instep level, said upper member being secured to said sole member around the margin of the heel rearwardly from substantially the heel breast portion on each side of said article and said upper member having a seamless vertical innermost surface along the extreme rear heel portion of said article, a foot-enclosing shell extending around the fore part of said article secured along its bottom margin to said sole member from substantially the heel breast portion on each side of said article and along its top margin to the lower margin of said upper member at a seam generally parallel to said sole member, and secured to said upper member along a zone generally normal to said sole member at substantially each heel breast portion, and a foxing overlying said seam formed by the juncture of the said top margin of said shell with the said lower margin of said upper member, said foxing being secured along its upper margin to said upper member and along its bottom margin to said shell.

4. An article of footwear comprising a sole member, a flexible upper member extending above ankle level and extending forwardly around the fore part of said article with its forward lower margin at about mid-instep level, said upper member being secured to said sole member around the margin of the heel rearwardly from substantially the heel breast portion on each side of the article and said upper member having a seamless vertical innermost surface along the extreme rear heel portion of said article, a relatively stiff form-retaining foot-enclosing shell extending from substantially the heel breast portion on each side of the article forwardly around the fore part of said article from the level of the said sole to about mid-instep level, said shell being secured along its bottom margin to said sole from substantially the heel breast portion of each side of said article and along its top margin to the lower margin of said upper member at a zone generally parallel to said sole member and se-

cured to said upper along a zone generally normal to said sole member at substantially each heel breast portion, a foxing overlying the seam formed by the juncture of the said top margin of said shell with the said lower margin of said upper member, said foxing being secured along its upper margin to said upper member and along its bottom margin to said shell, and a reinforcing counter overlying the outer face of said article around the heel thereof rearwardly of the shank of said sole member.

5. An article of footwear comprising a sole member, a flexible upper member extending at least to mid-calf height and extending forwardly around the fore part of said article with its lower margin at about instep level, said upper member being secured to said sole member around the margins of the heel rearwardly from substantially each heel breast portion of said article, a foot-enclosing form-retaining shell extending around the fore part of said article from the level of the sole to about instep level and secured along its bottom margin to said sole member from substantially the heel breast portion on each side of said article, secured along its top margin to the innermost surface of the lower margin of said upper member at a seam generally parallel to said sole member, and secured along the innermost surfaces of its rear margins to the outer surfaces of said upper member, said last-mentioned margins extending generally normal to said sole member at substantially each heel breast portion of said article.

6. An article of footwear comprising a sole

member, a flexible upper member extending at least to mid-calf height and extending forwardly around the fore part of said article with its forward lower margin at about instep level, said upper having a seamless vertical innermost surface along the extreme rear heel portion of said article and being secured to said sole member around the margins of the heel rearwardly from substantially each heel breast portion of said article, a foot-enclosing relatively stiff form-retaining shell extending around the fore part of said article from the level of the sole to about instep level and secured along its bottom margin to said sole member from substantially the heel breast portion on each side of said article, secured along its top margin to the innermost surface of the lower margin of said upper member at a seam generally parallel to said sole member, and secured along the innermost surfaces of its rear margins to the outer surfaces of said upper member, said last-mentioned margins extending generally normal to said sole member at substantially each heel breast portion of said article.
